UNITED STATES PATENT OFFICE

2,189,025

PAPER FEEDING DEVICE

Fred M. Carroll and John Henry Bakelaar, Binghamton, N. Y., assignors to International Business Machines Corporation, New York, N. Y., a corporation of New York

Application January 1, 1935, Serial No. 1

34 Claims. (Cl. 197—133)

This invention relates to improvements in paper feeding devices.

The improvements are illustrated as changes in the paper feeding devices disclosed in our co-pending application, Serial No. 659,442, filed March 3, 1933, which has eventuated in Patent 2,066,305.

An object of the present invention is to provide means for automatically feeding the record sheet a variable number of line spaces to skip the space between the printing of a heading and the recording of an item. A heading may consist of a name and address printed under control of perforated record cards. A perforation in the last address card initiates the skipping or spacing operation which continues until a cam settable for a required number of line spaces stops the paper in position for printing the first item. From there on, line spacing and ejection of the record sheet is carried on in the usual way.

Another object of the present invention is the provision of means for automatically initiating one or more line spacing operations subsequent to an ejecting operation usually at the end of a form. This is done in order that listing of a large group of items may be continued from one form to the next without printing items in the heading space at the top of a form. A feature of the head spacing control is the use of the same devices used to initiate and stop the space skipping operation set forth above.

Another object of the present invention is the provision of a plurality of driving gear trains for use in variable speed ejection or shifting of the record sheet. A fast drive may be selected for short movements or ejections of the sheet and a slow speed may be used for ejections longer than a predetermined space (3½ inches is taken as an example in the present case). A selection and interlock plate cooperates with the gear trains to prevent the connection of more than one gear train at a time.

A feature of the present invention is the provision of interlocks between the selected ejection spacing, the variable speed gearing and the gearing drive motor. This interlock includes an electric circuit through the drive motor including contacts operated by the ejection spacing and speed selection means. The contacts open to de-energize the motor when a fast speed gear train is selected at the same time that a setting is made for a long ejection. Then, either the slow speed gearing must be selected or the selection ejection length brought down to 3½ inches before

the contacts are again closed for feeding operation.

Another object of the invention is the provision of other interlocks between the sheet ejecting devices and the printer mechanism. The printer is stopped after total printing. This is done to allow time for the operation of the ejecting devices before resuming operation of the printer.

A further object of this invention is the provision of a removable record sheet frame with pin feed sprocket wheels which may be geared to the regular platen drive for automatic line spacing and ejection. The sprocket wheels are adapted to cooperate with continuous perforated borders on the side of standard register sheets. The sheets may be in duplicate or triplicate with interspersed carbons. They may vary in width and be wound on a roll or be arranged fan folded.

Another object of the present invention is the provision of devices for taking up the slack between a toothed ejection drive sector and a meshing pawl block on a link driven thereby. These devices prevent the jerk and impact of a late ejection pickup due to lost motion. As soon as ejection is initiated a spring actuated cam acts to close the space between the driving and driven teeth in the ejection device.

Another feature of the present invention is the provision of a common manipulative lever for operation of line spacing and ejection. The lever may be rocked in one direction to trip a line space control armature and moved in the other direction to actuate an ejection control armature.

A still further object of the present invention is the provision of a lock which is automatically operated as soon as ejection is initiated. This lock cooperates with a clutch between the platen and the ejection drive mechanism for the platen. The clutch is held closed during the ejection of the record sheet.

The devices of the invention are illustrated in a set of drawings which accompany and form part of the present specification.

In the drawings:

Fig. 1 is a side elevation of the paper carriage and feeding devices with a section taken through the printing mechanism.

Fig. 2 is a sectional elevation view taken at the left of the carriage and showing the housing containing the line spacing and ejection mechanisms.

Fig. 3 is section through the top of the housing covering the line spacing and ejection mechanisms showing a plan view of these devices.

Fig. 3A is a detail view of the clutch connections at the end of the platen shaft.

Fig. 4 is an elevation view of the two-speed gearing provided between the driving motor and the paper ejection shaft.

Fig. 5 is a sectional view taken along the line 5-5 in Fig. 4 and showing the interior construction of the two-speed gearing.

Fig. 6 is an elevation view of the line spacing control mechanism.

Fig. 7 is a side elevation view of the settable line spacing and ejection controls with the electrical contacts operated thereby.

Fig. 8 is a section of the paper spacing and ejection mechanism housing taken along line 8-8 in Fig. 7 and showing an end view of the contacts.

Fig. 8A shows a portion of a perforated record card.

Fig. 9 is an elevation view of the ejection clutch and driving mechanism.

Fig. 9A is a rear view of the eject sector assembly.

Fig. 10 is a front elevation view of a pin-feed attachment for the paper carriage.

Fig. 11 is a side view of the mechanism shown in Fig. 10.

Figs. 12A and 12B taken together form a wiring diagram of the electrical controls associated with the paper feeding and tabulating mechanisms.

Fig. 13 is a timing chart showing the time of operation of the cam contacts governing the operation of the paper feeding mechanisms.

Referring to Fig. 1, it is noted that the platen 51 is mounted on the carriage unit which in turn is supported on the tabulating frame 52 in position adjacent the type bars 53. The tabulating frame 52 carries a carriage supporting frame 54 (Fig. 2) which is provided with a series of rollers 55 for guiding and supporting the movable carriage frame 56. Attached to the right end of the carriage frame 56 is the carriage side plate 57 (Fig. 1). At the other end of the frame 56 is attached another side plate 58 (Figs. 2, 3 and 8) acting as a support for the left end of the platen holding members. Swinging between the side frames is a rectangular bar 60 (Figs. 3, 8 and 11) with ends in the form of trunnions 59 (Fig. 1) fitting in bearings on the side frames 57 and 58.

It is about this bar 60 that the platen 51 is swung through an angle of about 180 degrees in a counterclockwise direction to bring the platen in position to receive the end of the record material.

A bracket 61 (Figs. 3 and 8) attached to the left end of the rectangular bar 60 forms a support for one end of the platen, and the lever 62 (Figs. 10 and 11) forms the support for the platen at the other end. Parts 60, 61, and 62 form a bail which is pivotally mounted at 59 and adapted to be swung toward the rear of the machine. The lever 62 is provided with a handle 63 which may be grasped by the operator of the machine and swung in a counterclockwise direction through one half of a revolution to bring the platen into a raised record sheet receiving position.

The platen 51 is mounted on a shaft 69 which is carried in a bearing 70 (Fig. 10) on the lever 62 and the other end pivots in a bearing 71 on the bracket 61.

The record paper passes over a guide 74 (Fig. 11) and then is directed at a tangent to the

platen 51 and is drawn around the platen, under feeding rollers 75 and out beneath the cutting plate 76. The paper guiding and feeding devices are moved along with the platen when it is lifted from the normal position. The paper guide 74 is mounted on side plates 77 (Fig. 10) which are pivotally connected to the platen shaft 69 and to a shaft 78 suspended between the side plates 77 and links 79 pivoted at 80 on the carriage side frames 57 and 58. By means of this form of toggle link connection, the paper guide is adapted to maintain a position at an angle tangent to the platen when it is in a normal feeding position and in the raised paper inserting position.

The record paper is guided on the sides by guide members 72 (Fig. 3) in the form of bails which are supported on and movable along shaft 78. A finger piece 81 associated with the guide bail may be manipulated to move and lock the guide in a selected position.

The pressure feed rollers 75 (Figs. 3, 10 and 11) are supported on a shaft 82 which is held on overturned projections extending from a series of frames 84 pivoted at 85 on the rectangular bar 60. The pivot at 85 is formed by a projection on the frame 84 engaging a narrow slot cut in the rectangular bar 60.

The feed rollers 75 are normally held against the platen 51 by bow springs 86 (Fig. 11) each 30 of which is tensioned and held between a notch in frame 84 and a notch cut in the top of rectangular bar 60. The shaft 82 carrying the feed rollers 75 is provided with a pinion 89 secured in line with a gear 90 secured to the platen shaft 69. By means of this connection the feed rollers 75 are rotated whenever the platen is turned for a record feeding operation.

A means is provided to disconnect the feed rollers from engagement with the platen when it is desired to insert or remove record material. Each of the frames 84 carrying the feed rollers is formed with a projection 91 which is alongside the rectangular bar 60. Between projection 91 and bar 60 is placed a shaft 92, with a beveled side of the shaft cooperating with the end of the projection 91. The shaft 92 is held in this position by means of a groove cut in the side of rectangular bar 60.

A thumb piece 94 is attached to the shaft 92 to operate the same. When the shaft 92 is rocked, the frames 84 are moved in a clockwise direction about the pivot 85 to withdraw the feed rollers 75 from the platen 51.

The automatic feeding of the platen is brought about by connections cooperating with the left end of the platen shaft, as shown in Figs. 2, 3 and 8. The platen driving gear 107 (the actuation of which is described hereinafter) drives an idler gear 108 loosely mounted on the trunnion 59 of the rectangular bar 60. The connection continues through gear 108 meshing with the teeth 109 cut in a clutch member 110, which engages a clutch plate 111 secured to the platen shaft 69. The clutch plate 111 is formed with teeth 112 in the form of a star wheel.

Cooperating with the star wheel teeth in the clutch plate 111 is a roller 113 (Fig. 2) mounted on a lever 114 pivoted at 115 on the bracket 61 supporting the platen. A spring urges the roller 113 into depressions formed by teeth 112 and thus serves to locate the platen in a correct position for each line space.

When the platen is adjusted by hand, the clutch member 110 is forced to the left (Fig. 3A)

against the pressure of a spring 117 which normally holds it in engagement with the teeth on clutch plate 111. A collar 118 attached to the end of the platen shaft 69 forms an abutment 5 against which the compression spring 117 rests, the other end pressing against the clutch member 110. The gear 108 is wide enough to maintain engagement with gear teeth 109 when member 110 is out of clutching position.

When the platen is swung to the upper position, the gear teeth 109 cooperate with the stationary gear 108 to turn the clutch member 110 in a counterclockwise direction (Fig. 2). This rotating movement is not transmitted to the 15 platen shaft because the shaft is held by the cooperation between the star wheel 112 on clutch plate 111 and the detent 114.

On the downward movement of the platen there is a positive driving connection between 20 gear 108 and the platen shaft 69 unless the clutch member 110 is shifted to the left (Fig. 3A) and disconnected from plate 111. For this reason, lever 119 (Figs. 2, 3 and 3A) is provided to shift clutch member 110. The clutch lever is pivoted at 120 on bracket 121 secured to the 25 trunnion 59 of the rectangular bar 60. The lever cooperates with the clutch by means of an arcuate offset 122 thereon engaging in a groove 123 in clutch member 110 as the platen is lifted or 30 lowered into position. The clutch lever 119 is provided with a finger piece 124 which may be manipulated to disconnect the clutch members when it is desired to back-space the platen.

An adjustable means is provided to control the 35 time of engagement of the clutch member 110 with the plate 111 as the platen is lowered, thus providing for the feeding of an inserted strip to bring any desired amount of head spacing above the printing line for the first item. This is 40 brought about by camming the lever 119 to de-clutch the platen for a portion of its downward movement, and releasing the lever to permit the clutch connection to take hold during the remaining part of the motion. The cam surface 125 45 (Fig. 3A) which cooperates with an extension 126 on the side of lever 119, forms an annular part of a disk 127 loosely pivoted on trunnion 59. The disk has a raised annular ring 128 which is knurled on the top face to permit circular adjustment by hand. A portion of the periphery of the disk is cut to form teeth 129 (Fig. 2) for locating and locking the disk in position. Cooperating with the teeth 129 is a locking member 130 slidably mounted on pin projecting from 50 carriage frame 58.

A screw 132 may be tightened to hold member 130 against frame plate 58 after the disk 127 has been brought around to the desired head spacing position. As the disk 127 is moved in a counter-clockwise direction (Fig. 2) the end of the raised cam portion 125 is brought closer to the projection 126 on the lever 119 when the lever is in the raised position.

Then, as the lever is swung to the lower position along with the platen, it reaches the end of the cam whereupon the lever 119 is permitted to rock in a counterclockwise direction (Fig. 3A) to shift the clutch member 110 and connect the platen so that it is driven from the time the 65 projection 126 reaches the end of the cam until the clutch lever is brought to the home position. Each of the notches 129 represents a space of one line of head spacing.

The mechanism described hereinbefore is situated around the platen and between the platen

side plates 57 and 58. Other automatic mechanism is provided to control rotation of the platen. This mechanism, which is about to be described, is compactly arranged and formed as a unit which is secured to the left side of the 5 platen frame. The only driving connection between this automatic carriage control unit and the other carriage control mechanism is through the gear 107 (Figs. 2 and 3).

The automatic carriage control unit is provided 10 with manually adjustable mechanical arrangement for varying the line spacing, determining whether ejection is to occur or not, selecting the speed of ejection, setting the distance on the record between the heading and the first item setting 15 the length of form to be printed upon and setting the number of lines to be printed before ejection. Other electrical switches may be adjusted to control the unit so that line spacing may or may not be effected by the occurrence of a 20 total, spacing under listing and tabulating control, and spacing without cards in the tabulator.

Adjustments may be made to secure ejection after every item, ejection according to the occurrence of minor or major group control 25 changes, or ejection at the presentation of the end of a record form. A motor drives the mechanism in the unit according to the setting of the controls mentioned. The entire unit is secured to the carriage frame and is moved along with 30 the same to the various transverse printing positions.

The automatic carriage control mechanism is held in a frame comprising a casting 134 (Figs. 2 and 3) secured to the carriage side plate 58 and 35 guide frame 56. The casting frame 134 forms a support for the carriage motor CM. A casing plate 133 attached to frame 134 forms a cover for the speed changing gearing. A number of bosses project from the inner side of the casting 40 frame and attached to some of these is a center plate 138 (Fig. 3) which acts as a support for many of the shafts in the unit. The mechanism projecting beyond the plate 138 is protected by a cover 139 which coincides with the contour of 45 the frame 134 making an enclosed box-like unit of the carriage control mechanism.

A bracket 141 (Fig. 5) projecting from the carriage frame 134, forms a bearing for the shaft 142 of the carriage motor CM. A pinion 143 on 50 the motor shaft 142 meshes with a gear 144 pivoted on a stud 145 on the side of bracket 141. Attached to gear 144 is a smaller gear 135 in mesh with a gear 136 keyed on the shaft 137. On the side of gear 136 is secured a gear 93 in mesh 55 with an idler gear 94 (Fig. 4). The driving train of connections continues through gear 94 meshing with another idler gear 95 which in turn drives a gear 96 fastened to the line spacing drive shaft 151. The gear connections just traced form a 60 constantly running train from motor shaft 142 to line spacing drive shaft 151. Other gearing, also under the cover 133 with the line space drive, forms a selective two speed drive for the ejection mechanism described hereinafter.

Continuing the tracing of the line space drive, reference to Fig. 6 shows that shaft 151 carries a clutch plate 152 attached thereto. Adjacent the toothed plate 152 is a cam 154 loosely pivoted on shaft 151. This cam carries a clutching pawl 70 155 pivoted at 156. A compression spring 158 mounted in a stud on cam 154 tends to engage pawl 155 with clutch plate 152, but an extending tail on the pawl is normally obstructed by the end of a lever 160 connected to the armature 161 of 75

- the line spacing magnet LSM. The lever 160 is pivoted on a stud 162 and is urged in a counter-clockwise direction against stop pin 163 by a spring 164.
- 5 When the line spacing magnet LSM is energized, the lever 160 is rocked in a clockwise direction, releasing the clutch pawl 155 which then engages the clutch plate 152, thus connecting the cam 154 to the driving shaft 151. As the cam 154 10 rotates, it operates a lever 168 through a roller 169 on the lever in cooperation with the periphery of the cam. The lever 168 is pivoted on a stud 170 and is provided with an extending arm which is cut to form three notches. A link 172, placed 15 adjacent the lever 168, carries a pin 173 adapted to cooperate with any one of the three notches in lever 168. The other end of link 172 is pivotally connected at 174 to a line spacing plate 175 loosely mounted on the platen feed shaft 176.
- 20 The plate 175 carries a feed pawl 177 pivoted at 178 in the plate and adapted to cooperate with a ratchet gear 179 fixed to shaft 176. This shaft is secured to gear 107 (Fig. 3) and thereby is adapted to turn the platen.
- 25 From the connections mentioned, it may be noted that as the cam 154 (Fig. 6) is rotated, the lever 168 is rocked in a clockwise direction, pushing link 172 down and rocking the plate 175 so that pawl 177 advances the platen shaft 176 30 one or more steps in a counterclockwise direction.
- The amount of motion imparted to the platen feed shaft is determined by the adjustment of the end of link 172 so that pin 173 cooperates with any one of the three notches in lever 168.
- 35 If the pin cooperates with the notch nearest the pivot of the lever, the motion imparted will amount to one line space. When the link is lifted to cooperate with the center notch the motion carried to the platen amounts to two line 40 spaces. Lifting of the link to the highest position causes cooperation with the end notch in lever 168 and connects the line spacing devices to produce three steps of motion.
- The manual adjustment of link 172 is brought 45 about by means of a manipulated arm 180 (Fig. 2) extending from the side of the carriage frame 134. The arm 180 carries a knob 181 with a plunger which the operator may set to hold the arm in any one of the three positions identified 50 on the side of the frame. A shaft 182 (Fig. 6) is connected to the arm 180 and has secured thereon another arm 183 with a tab 184 cooperating with the side of link 172. By means of these connections the link 172 is swung to a 55 space selecting position by arm 180. The link is held against the side of lever 168 by a guiding strip 185 secured to lever 168. A spring 186 urges the lever 168 in a counterclockwise direction and tends to hold roller 169 against cam 154.
- 60 Link 172 is held in constant cooperation with tab 184 by means of a spring 64.
- A spring 187 wound around stud 178 tends to move pawl 177 into cooperation with ratchet gear 179. However, in the normal position of 65 the parts, a cam face on the lower portion of pawl 177 cooperates with a stud 188 projecting from the frame 134 in such manner that the pawl is forced away from the gear. The same stud 188 serves as a stop for the plate 175 when 70 it is drawn to the home position by a spring 189.
- Secured to the side of ratchet gear 179 is a star wheel 190 provided for the purpose of normally preventing backward movement of the line spacing shaft 176. Cooperating with the star wheel 190 is a pawl 191 loosely pivoted on shaft 192 and held into cooperation with the star wheel by spring 193. At certain times in the operation of the machine, the pawl 191 is disengaged from the wheel 190 by a link 194 which is slotted to engage a pin 195 on the pawl to depress the pawl 5 as explained hereinafter.
- In addition to the above described line spacing connections to the platen drive shaft 176, other devices are provided to feed or eject the record paper for wide spacing. Many of the 10 gears previously mentioned, namely; gears 144, 135, 136, 93, 94, 95 and 96 (Figs. 4 and 5) are used in ejecting as well as line spacing. Attached to gear 96 is a gear 65 meshing with a gear 66 keyed to a shaft 67. This shaft 67 is 15 similar to the other shaft 137 (Fig. 5) in that it may be moved axially to place a pinion 87 thereon in and out of mesh with an eject drive gear 68. The other shaft 137 terminates in a similar pinion 88. Shaft 137 operates at a 20 higher rate of speed than shaft 67, because the former is geared almost directly to drive pinion 143 while the latter is driven through a train of gearing involving two speed reductions between gears 93, 94 and 65, 66. The machine 25 operator may choose the speed of record ejection according to the distance or space to be ejected. For spaces less than 3½ inches it is advisable to use the high speed train of ejection gearing, while for all longer lengths the low 30 speed train should be used.
- The shafts 67 and 137 are held in and out of driving position by wire spring clips 73 cooperating with pairs of grooves 97 and 98 in the shafts. If it is desired to select the slow speed 35 shaft 67, the knurled screw head 99 thereon is grasped and pulled to the left (Fig. 5) until pinion 87 meshes with gear 68 and clip 73 engages groove 98. This axial movement of shaft 67 takes place without disturbing gear 66 because of 40 the key connections 101 between the two permitting relative axial displacement but maintaining a fixed association in rotation. In the same way, if it is desired to engage the high speed train 45 of ejection gearing, a knob 100 is grasped and shaft 137 is pulled to the right until pinion 88 is in mesh with gear 68 and clip 73 drops into groove 97. The cover 133 is cut out to give access to knobs 99 and 100.
- An interlock is provided to prevent the engagement of more than one gear train at a time. A supporting plate 102 (Fig. 4) for the interlocking devices is attached to stud 145 and another stud 103 fixed in casting 134. Protruding from a screw stud 147 in the center of plate 102 is a 55 loosely pivoted knurled knob 104 carrying an interlock disk 105. Two semi-circular notches 126 and 127 are cut in the periphery of disk 105. The concentric edge of the disk cooperates with shoulders on the left ends (Fig. 5) of the shafts 67 and 137 to prevent axial displacement. It is only when the disk is turned to bring one of the notches into position with an associated shaft that the shaft is free for axial movement. As shown in Fig. 4, the notch 127 is concentric 60 with shaft 137 adapting the gearing for selection of the high speed gears, while shaft 67 is locked in an ineffective position by the edge of disk 105. If it is desired to select the slow gear train, knob 104 is grasped and turned to bring notch 126 70 to coincide with shaft 67. The edge of the disk cooperates with the ends of the bushings carrying gears 136 and 66 to hold the gears towards the right, Fig. 5, as the shafts are pulled to the left.

The disk 105 is held in an adjusted position by a detent pin 106 cooperating with a pair of depressions 128 in the edge of the disk. The pin is riveted in a detent lever 116 pivoted on stud 127 on the side of plate 102 and urged by spring 128 into cooperation with the disk. A third depression 129 in the disk 105 marks a position wherein the disk may be stopped by the detent to lock both trains of gearing out of operation 5 when ejection movement of the record paper is not desired. A slot 131 in disk 105 cooperates with a screw 146 on plate 102 to limit the movement of the disk.

Cooperating with disk 105 is part of an electrical interlock preventing the operation of the paper feeding devices when the high speed gear train is improperly selected for a long paper ejection feed of more than 3½ inches. A cam 148 riveted on the side of disk 105 cooperates with a lever 149 pivoted on stud 103 and formed with an offset lug 150 engaging the side of an insulation block 153 on one blade of contacts 157. When the high speed gear train is selected, lever 149 is rocked in a counterclockwise direction to 25 open contacts 157. These contacts are fastened to insulating bars on frame 134 and wired in series with the circuit energizing the drive motor CM. Thus the motor is disabled as a high speed drive is selected unless other connections are 30 made to complement the selection. Other contacts described hereinafter are in parallel with the contacts 157 in the motor circuit and are closed when an ejection of less than 3½ inches is selected. The tension in the contact blade 35 carrying block 153 tends to close contacts 157 so that when disk 105 is moved to select the low speed gears or lock both gears, and cam 148 moves out of the path of the end of lever 149, the lever is rocked in a clockwise direction by a 40 spring 158 to allow the closing of contacts 157 and energization of motor CM.

The ejection driving connections continue through a clutch which may be connected at any time in the operation of the machine to cause a 45 paper ejecting operation. The driving member of the clutch is the gear 68 driven by either of the pinions 87 or 88, previously mentioned. Referring to Fig. 9 it is noted that gear 68 is pivoted on stud 171 in frame 134 and carries attached 50 thereto a toothed clutch plate 197. Loosely pivoted on the same stud 171 is an ejecting cam plate 200. Pivoted on the side of cam 200 is a pawl 198 on stud 199. The pawl is in alignment with clutch plate 197 but is normally held out 55 of engagement therewith by a lever 201 abutting against an extending tail on the pawl. The lever is pivoted at 202 and attached to an armature block 203 associated with the ejecting control magnet EM. A compression spring 165 on cam plate 200 presses against the pawl and tends to engage it with the clutch plate. When the magnet EM is energized, lever 201 is rocked 60 in a clockwise direction, releasing pawl 198 and clutching the ejecting cam plate 200 to the driving gear 68.

Either ejecting or a line spacing operation may be effected by a manual adjustment on the outside of the carriage control unit. This is done by manipulation of a lever 204 (Fig. 3) 65 which may be moved in one direction to actuate the eject armature 203 (Fig. 9) and moved the other way to trip the line space armature 161 (Fig. 6). The lever 204 is pivoted on the end of stud 202 and formed with three arms one of 70 which is bent to project out of an aperture in

case 134 in position to be grasped by the fingers of the operator of the machine. The second arm is formed with an offset 205 (Fig. 9) overlying armature 203. The third arm carries a stud 206 (Fig. 6) which acts as a terminal for a rod 5 207 reaching down into contact with armature lever 160. A spring 208 attached to stud 206 tends to hold the lever 204 in a centralized position.

Movement of the lever in a clockwise direction 10 (Figs. 6 and 9) causes an eject operation and movement in a counterclockwise direction causes a line spacing operation, the clutch mechanisms being actuated just as though magnet EM or magnet LSM were energized.

Before describing the other connections for performing an ejecting operation, it is believed well to mention that such an operation may take place at any point during printing down the length of a record sheet. Ejection is initiated 15 by energization of magnet EM on the occurrence of a total, after a certain number of lines, or at the end of a form. In Fig. 7 the ejecting devices are shown in the normal position. There it is noted that a link 210 is articulated at 211 on 20 side of plate 200 and at the other end it is pivoted connected at 212 to the side of an ejecting frame 213 (Figs. 9 and 9A) pivoted at 209 on the frame of the control unit. This rocking 25 eject frame 213 is formed in the shape of an arc and carries a similarly shaped plate 247 with a series of teeth 214 cut in the inner side of the arc. Cooperating with these teeth is a block 215 formed with a single tooth 216 adapted to ratchet over the teeth 214 and engage any one 30 of the teeth as a link 217 carrying the block 215 is drawn along the inner surface of the arc during line spacing operation. The block 215 is loosely pivoted on link 217 by means of a stud 218 mounted on link 217. An arcuate guide strip 35 219 secured to plate 247 cooperates with a groove in the top of block 215 and serves to hold the block in alignment with teeth 214. When the clutch connection comprising pawl 198 (Fig. 9) and clutch plate 197 is made effective by the 40 energization of the magnet EM or by rocking lever 204, the plate 200 is connected to turn in a clockwise direction and moves link 210 and frame 213 to the right with a gradually accelerated motion until the plate 200 has moved 45 through an angle of ninety degrees and then the motion is retarded until the link is practically at rest as the plate reaches a position 50 after 180 degrees of motion.

Then the same type of motion is repeated as 55 the plate goes through the final 180 degrees in arriving back to the home position after a complete revolution.

Continuing now with outlining the connections of link 210 to the line spacing devices for 60 the purpose of ejection, it is noted that in its motion to the right the link carries along the ejecting frame 213 by rocking it in a clockwise direction about the pivot 209. As this is done, the teeth 214 on the eject plate 247 engage the block 215 on the end of link 217 and move this link to the right. The right end of link 217 is connected by a stud 246 to a sector 220 loosely pivoted on a shaft 221. The sector teeth are in mesh with a pinion 222 which may be clutched to the line spacing shaft 176, which, as noted hereinbefore, serves to space the platen through the connections to gear 107 (Fig. 3).

Referring to Fig. 8 it may be seen that shaft 70 75 176 is carried in a bushing 223 projecting from

center plate 138 and extending in alignment with the hub on gear 107. Adjustably secured to the end of shaft 176 by screws is a collar 225 provided with a projection 227 adapted to cooperate with a notch 228 (Fig. 9) cut in the side of pinion 222. If the pinion 222 is held out of cooperation with the projection 227, the motion of sector 220 is not imparted to the line spacing shaft 176. The pinion 222 may be moved and held out of engagement with the shaft 176 when it is desired to prevent ejection. The pinion is positioned by a shaft 229 (Figs. 3, 7 and 8) carrying a positioning member 230 which cooperates with a circumferential groove 231 (Fig. 8) cut in the pinion 222.

A pin 240 on the member 230 cooperates with a hole located in the bushing 223 and serves to hold the member in cooperation with the pinion. At the other end of the shaft 229 (Figs. 2 and 3) is mounted a knurled knob 232 attached to a positioning blank 233 cooperating with the pin 234 projecting from the side of frame 134. Another pin 235, slightly higher than pin 234, cooperates with an elongated notch 236 cut in the side of member 233. By means of the pins and the member 233, the shaft 229 may be positioned axially in two different ways. If the knob 232 is grasped by the operator and pulled to the right (Fig. 3) and given a counterclockwise twist (Fig. 2) the pin 234 holds the shaft 229 in this extended position by obstructing the return movement of the shaft to the left as seen in Fig. 8. When the shaft is in position, pinion 222 is declutched from the shaft 176 and automatic ejection is prevented. If the operator wishes to, set the devices for ejection, the knob 232 may be turned in a clockwise direction until a notch 237 (Fig. 2) in member 233 coincides with pin 234. Then the shaft 229 may move to the left (Fig. 8) carrying lever 230 and pinion 222 to the left and engaging the pinion with the driving projection 227 on the line spacing shaft 176. A compression spring 239 placed between member 230 and bushing 223 tends to hold the pinion 222 in engagement with the collar 225. With the pinion so connected, any clockwise ejection movement of the sector 220 is transmitted through pinion 222 (Fig. 19), shaft 176, gears 107 and 108, clutch member 110 and clutch 111 to turn the platen shaft, and the converse is true in that if the shaft 176 is spaced in line spacing by means of the clutch plate 179, the sector 220 will be advanced step by step in a clockwise direction (Figs. 7 and 9) as line spacing takes place.

As sector 220 is rocked step-by-step to the right in line spacing, the tooth 216 (Fig. 7) ratchets idly over tooth after tooth along the line of teeth 214, while member 213 and plate 247 are in a horizontal position. Then, at any selected point in the operation, and when tooth 216 is in mesh with any of the teeth 214, ejection is performed by rocking member 213, pushing link 217 connected thereto through tooth 216 and block 215, rocking sector 220, turning gears 222, 107, 108, 109, 112 and the platen.

After sector 220 is moved in a clockwise direction (Fig. 9) it is restored by a compression spring 242. A link 243 is pivoted at 244 on the side of sector 220. At the lower end the link is connected to a bell crank 245, pivoted at 238 on plate 138. The crank carries a link 226 with a terminal abutting one end of the spring 242 the other end of which is supported in the casting frame. The counterclockwise restoring movement of sector 220 under the urging of spring

242 does not effect any movement of the platen shaft, because the clutch plate 111 thereon and drive member 110 form a one way clutch for driving in the other direction.

A governor is connected to sector 220 through gear 107 (Fig. 1) to prevent a speedy restoration by spring 242. This centrifugal governor 651 is pivoted on stud 652 and carries a pinion 653 meshing with an idler gear 654 in mesh with platen drive gear 107.

When the sector 220 is moved to the extreme adjusted position by the actuation of ejecting member 213, the teeth 214 arranged in an arc on member 247 form a perfect arc about the center 246 where link 217 is secured to sector 220. The radius of the arc is substantially the same as the length of link 217 and thus all teeth 214 are equi-distant from the center 246 in the sector 220 when it is in the extreme eject position.

The mechanism is designed in this way so that the sector 220 never moves beyond a certain position in ejection regardless of the point at which ejection is started by the engagement of one of the teeth 214 with the toothed block 215 on link 217. If, at the time ejection is initiated, the block 215 engages a tooth 214 near the center 209, the ejection movement of sector 220 is short. On the other hand, if upon ejection initiation the block 215 engages a tooth 214 near the end of member 213 removed from center 209, the ejection movement of sector 220 is long even though the extreme ejection position of the member 213 is the same as during short ejection.

When the sector 220 reaches the extreme clockwise adjusted position as result of a plurality of line spacing operations, devices are operated to prevent further spacing operation. Line spacing at such a time would move the sector too far in a clockwise direction and demesh pinion 222. An interlock is provided to hold the armature lever 160 (Fig. 6) in position to prevent the release of the spacing clutch pawl 155. The parts comprising the interlock include a lever 421 pivoted on a stud 422 extending from frame 134. A pin 425 (Figs. 7 and 9) on the side of sector 220 is so positioned that it strikes an offset 423 (Fig. 6) on lever 421 when the sector is moved to the end of its stroke. On the same stud with lever 421 is pivoted a retaining member 426 which is held in cooperation with the lever by a spring 427 between the two. One end of member 426 cooperates with a lug 424 on lever 421. When the lever is struck by pin 425 and rocked in a clockwise direction, member 426 follows in the same direction with the left end thereof abutting underneath the lever 160 attached to the line space armature 161. Thus operation of the armature lever is prevented by the resistance of spring 427 which can only be overcome by positive operation of lever 204.

When lever 160 is held, it in turn maintains the ineffective positioning of line space pawl 155 to prevent further line spacing of the record sheet. A spring 428 serves to hold member 426 ordinarily in a normal position against a stop stud 429 and out of the path of lever 160.

On the return counterclockwise motion of the sector 220 (Figs. 7 and 9) under the pressure of spring 242, the ratchet plate 247 is withdrawn from the toothed block 215 by means of devices 70 mounted on the ejecting member 213. This is done to permit a free movement of the block and link 217 to the left in returning to normal position. A pair of cranks 248 and 249 are pivoted on eject member 213 by means of studs 250 and 75

251 which are fixed in the member. The two cranks are pivotally connected to the toothed plate 247 by studs 254 and 255 on the plate which are encircled by arcuate slots 252 and 253, respectively, in the cranks 248 and 249. The plate also is slotted at 296 and 297 to clear the two fixed studs 250 and 251 on member 213. Thus the plate 247 is adapted for both vertical and horizontal shifting with respect to member 213. A link 256 connected between the two lower ends of the cranks, completes a parallelogram linkage comprising plate 247, both cranks and the link. If crank 249 is rocked in a counterclockwise direction (Fig. 7) about stud 251 it is apparent that plate 247 will be lowered an equal amount at both ends of the line of teeth 214. A latch 257 pivoted at 258 on member 213 is formed with a shoulder cooperating with the end of crank 249 to prevent such a plate lowering motion of the cranks. It is only at the mid-point of the eject operation, when member 213 is rocked to an upright position, and a lug 140 on latch 257 strikes a stud 166 on the frame, that the crank 249 is released and a spring 167 attached to the other crank 248 operates the linkage to move the plate 247 so that the teeth 214 are out of the path of the tooth 216.

Near the end of the eject restoring operation, an extension on crank 249 strikes a fixed pin 240, 30 rocking the crank in a clockwise direction about pivot 251 and raising plate 247 with teeth 214 again in cooperation with tooth 216. At the same time latch 257 springs back under the arm of crank 249 to hold the entire linkage in normal 35 position.

A coil spring 642 (Fig. 9) presses between an abutment 641 fastened to link 217 and a terminal link 643 pivoted on sector 220. The object of this construction is to hold link 217 down with 40 toothed block 215 thereon urged into cooperation with teeth 214.

It is noted that because of the slots 252 and 253 (Fig. 7), plate 247 is free to move back and forth a slight amount with studs 254 and 255 thereon moving in arcuate slots 252 and 253 in a direction along the length of member 213. This construction is devised for moving plate 247 to the right (Fig. 7) to bring the nearest tooth 214 against tooth 216 to eliminate slack and lost 45 motion at the very beginning of the ejection operation. The sliding movement of plate 247 is brought about by devices cooperating with the stud 255 on the plate. Referring to Fig. 9, it is seen that stud 255 protrudes into a cam slot 461 in an arm 462 pivoted loosely on stud 209. The slot 461 is shaped so that when the arm is rocked in a counterclockwise direction the plate 247 is drawn to the right. A spring 463 urges the arm 462 in that direction but it is normally prevented from moving because of an abutment 464 in the path of a projection 465 on the arm. The abutment is formed on a lever 466 (Fig. 9A) pivoted at 467 and articulated to an operating arm 468 (Fig. 9) by a link 469. The operating 50 arm 468 is fixed to a shaft 470 and at the upper end rests on a segment plate 471 fastened to the ejection operating disk 200. Since disk 200 turns in a clockwise direction in ejection, at the very start of the operation, arm 468 drops off the upper concentric surface of segment 471.

In dropping the arm pushes down link 469 and rocks lever 466 in a counterclockwise direction (Fig. 9A) releasing arm 462 so that spring 463 may move the arm to draw it down. As the arm lowers (Fig. 9) the cam slot 461 therein shifts

the stud 255 and connected plate 247 to the right until contact is made between a tooth 214 and tooth 216. This is all done at the instant ejection is initiated. There follows a quick pickup of link 217 and driving of the sector 220 by the 5 rocking of member 213 and the attached plate 247.

Early in the second restoring half of the ejection cycle, a cam face 472 on segment 471 strikes the end of arm 468 and moves it up on the concentric edge of the segment. This movement is communicated to lever 466 and the abutment 464 thereon is brought back into normal position obstructing the downward movement of the projection 465 on arm 462. Thus the plate 247 is 10 shifted back to the left at the end of the ejection operation.

The arm 468 is connected through shaft 470 to other devices for locking the clutch 111 (Fig. 3A) closed as soon as the paper ejection operation starts. In Fig. 2 it is shown that the inner end of shaft 470 carries an arm 473 which is connected to a bell crank 474 by a link 475. The crank is pivoted at 476 and formed with a shoulder 477 adapted to cooperate with extension 478 25 on lever 119. It is remembered that this lever 119 serves to connect and disconnect the clutch wheel 110 and wheel 111 through the connection of offset 122 in groove 123 of wheel 110. A spring 479 attached to arm 473 tends to rock the 30 shaft 470 but is prevented from doing so by the obstructing segment plate 471 (Fig. 9) which prevents the rocking of arm 468 attached to the other end of shaft 470.

However, as soon as plate 471 is moved in a 35 clockwise direction, arm 468 is free to fall under the urging of spring 478 (Fig. 2) and bell crank 474 is rocked in a clockwise direction to place shoulder 477 against the left side of extension 478 (Fig. 3A) thus camming and holding the clutch 40 111 closed during the driving portion of the ejection cycle.

Another interlock is operated as soon as ejection is initiated. This mechanism serves to pull the detent 114 (Fig. 2) normally cooperating 45 with the line spacing star wheel teeth 112 out of cooperation to eliminate the noise that would otherwise attend the rapid skipping of the detent from tooth to tooth during the ejection spacing. Mounted on the screw stud 212 (Figs. 2, 3, 7 and 9A) connecting link 210 and member 213 is a cam lever 481 cooperating with an arc shaped lever 482 (Fig. 2) secured to a shaft 483. Secured to the other end of shaft 483 is an arm 484 carrying a link 485 guided by a screw 486 on 50 the side plate 58. The end of the link is formed with an upward extension 487 engaging behind a lug 488 on detent arm 114. A spring 489 is attached to another lug on the end of detent 114 and tends to hold the positioning roll 113 thereon into contact with the teeth 112 of the clutch star wheel 111. However, as soon as link 210 (Fig. 7) is pulled up in ejection, the stud 212 is moved in an arc about center 209. A pin 491 in member 213 prevents cam 481 from rocking 65 on pivot 212. The cam 481 (Fig. 2) carried thereon strikes a cam face 490 on the inner face of a lever 482, rocking the lever in a clockwise direction. Arm 484 is rocked along therewith and pulls link 485 to the right. The end 487 of 70 the link engages lug 488 and rocks detent 114 in a counterclockwise direction about center 115, thus moving roll 113 away from teeth. This ineffective position of the detent is maintained during the operating half of the ejection cycle because 75

the inner arcuate edge of lever 482 contacting cam 481 is concentric with the path of the cam after the lever is rocked.

At the end of the first half of the ejection stroke, the cam 481 moves beyond the upper end of lever 482 and then the lever is free to move in a counterclockwise direction to normal position as urged by spring 489. Detent 114 follows along therewith to again position the star wheel. Cam 481 does not disturb lever 482 on the downward restoring movement of member 213, because the cam is free to turn in a counterclockwise direction (Fig. 2) on pivot 212. A coil spring 492 (Fig. 3) urges cam 481 to normal position against pin 491 at the end of the cycle when the cam passes below cam face 490.

The return stroke of sector 220 may be adjustably varied to determine the length of the record sheet form to be printed upon in the machine.

20 The form may be shortened by stopping the sector 220 at any point along its travel towards the left (Fig. 7). For this purpose, a lever 259, pivoted on shaft 221 carries a stopping block 493 cooperating with a stud 260 mounted on the side. 25 of sector 220. The upper end of the form length setting lever 259 is adapted to be adjusted around and held in any position along an arc formed by a segmental index plate 261. This index plate is secured at 264 to a frame plate 262 which is held to casting 134 by screws 263, and at the other end the index plate encircles shaft 265. The surface of the index plate is inscribed with long lines representing inches of spacing, and short lines representing lines of printing spacing. A 30 pointer 266 is formed on the end of lever 259 opposite a gripping plate 497 to indicate the length of sheet selected. The bottom edge of plate 261 is formed with rack teeth 267 which are engaged by a key in the shape of a pinion that is inserted 35 in aperture 495 and turned to move lever 259 and sector 220 to a selected position against the pressure of spring 242.

When the selected position is reached, the lever may be locked in place by turning a nut 496 on a 45 screw passing through the gripping plate. Corrugations on plate 261 and lever 259 lock the lever in place when plate 497 is drawn towards lever 259 to pinch index plate 261 therebetween. As shown in Fig. 7 the lever 259 and sector 220 50 are positioned to handle record forms 12 inches in length.

It is mentioned hereinbefore, with respect to selection of speed of ejection, that contacts 157 (Fig. 4) are opened if a high speed gear train is selected and that other contacts must be closed by a selection of less than 3½ inches of ejection spacing. These other contacts 499 (Fig. 7) are closed by lever 259 when said lever is set for a length of form shorter than 3½ inches. A cam face 504 on lever 259 cooperates with a tab 502 formed on a lever 500 pivoted at 501 on the side of frame plate 262. The bottom of a vertical arm on lever 500 cooperates with contacts 499 so that when the lever is rocked in a clockwise direction by cam face 504, the contacts are closed. A spring 503 is adapted to hold lever 500 in an inoperative position when lever 259 is moved to the left to select forms longer than 3½ inches. The wiring of contacts 157 and 499 to 70 the operating motor CM is described more fully hereinafter.

A series of contacts are employed to control the ejection and line space magnets and the tabulating start and stop devices. These contacts are supported on the inside of the casing 134,

139 and near the front of the machine. In Figs. 3, 7 and 8, it is seen that a channel bar 505 supports three blocks 506, 507 and 508 each holding a pair of contacts. The channel is secured to casting 134 and formed to hold stud 509 and shafts 510 and 511 supporting the operating members for the contacts.

The machine is provided with devices for skipping a variable amount of space between the last item of a heading and the printing line for the 10 first item on the form. It is described hereinafter how the line spacing magnet LSM is energized to start the skipping operation. After an adjustable amount of the form is fed the space skipping is stopped by opening contacts 498 (Fig. 7) by devices about to be described.

The skip stop contact 498 is held closed by a bell crank 512 fastened to shaft 510. The crank in turn is held by a latch 513 pivoted on shaft 265 and formed with a shoulder engaging a lug 514 on the crank. At the end of the latch is pivoted a flipper 515 on stud 516. The latch is operated by an adjustable tripping lever 517 fastened to an arcuate slotted plate 518 secured to sector 220. The upper end of the lever 517 is formed with a pointed cam face which cooperates with flipper 515 to rock the latch and release the bell crank 512. Because the mounting of flipper 515 is uni-directional, the latch 513 is tripped only when lever 517 passes in a clockwise direction. A pointer 519 on the lever 517 may be set to the proper point along scale 261 so that the first item may be printed at any line of the record form. As shown the skip stop is set for 2 inches which is the space allowed between the 30 top of a heading and the first item. A screw and nut connection 520 extending through lever 517 and a slot 521 in plate 518 may be moved along the slot and fastened in the desired position. If the skip stop operation is not needed, lever 517 40 may be moved to the right end of the slot.

When bell crank 512 is released, a spring 522 urges it in a clockwise direction to lower an insulation finger 523 away from contacts 498 and against contacts 292. Thus contacts 498 are 45 opened and contacts 292 are closed for purposes described more fully hereinafter. The shaft 510 is attached to bell crank 512 so that it also turns to place an arm 524 (Fig. 6) thereon in the path of a roller 525 on the line space operating arm 50 168. The roller serves to restore the bell crank to the latched position shown in Fig. 7.

As explained hereinbefore, the ejecting operation is controlled by the energization of magnet EM. This magnet is energized at various times 55 according to the setting of the controls and the closing of contacts to form a completed circuit. For one form of control the contacts are closed as the printing on the record form approaches the end of the form. These contacts 269 (Fig. 7) 60 are operated by an insulation finger 270 fastened to one end of a lever 271 pivoted on stud 509. The other end of the lever is formed with a lug 272 engaged by a latch 273 pivoted on shaft 265 alongside latch 513. Latch 273 is operated at a 65 selected point in the feeding of a record form, by a cam face on the upper end of an eject lever 274 loosely pivoted on shaft 221 and held in place by a nut and screw 275 projecting through slot 521. A pointer 526 on the lever indicates the 70 inches of space through which the record form is line spaced before ejection begins.

When lever 271 is in the normal position, insulation finger 270 holds contacts 405 closed for reasons set forth hereinafter. However, when 75

lever 274 strikes latch 273, lever 271 is unlatched and free to rock in a clockwise direction as urged by spring 527. Thus finger 270 is lowered to open contacts 405 and close contacts 269 which are in series with the eject magnet EM and adapted to initiate an eject cycle of operation.

The lever 271 is restored by a link 276 connected thereto by a pin and slot formation 277. Individual coil springs 278 restore latches 271 and 518.

When an eject operation takes place, various electrical and mechanical devices in the machine must be operated to control carriage feeding, the operation of the carriage motor, the disablement of the line space latch, and the operation 15 of the tabulating machine. Contacts are operated to cause a delay in the restarting of the tabulating driving connections during an eject operation. Other disengagements must be effected to 20 free the line spacing shaft from ratchet connections during ejection. These and other controls to be described hereinafter with reference to the wiring diagram are effected by the cam faces formed on the periphery of plate 200 (Fig. 9) 25 which, as is noted from the foregoing section of the description, turns through a complete clockwise revolution during an ejecting operation.

Cooperating with the cam plate 200 is a contact operating lever 279 pivoted at 280 on plate 138 30 and drawn by spring 281 into contact with the periphery of the cam plate. The upper end of the lever 279 is formed with a projection 282 which acts as a cam face and also as a latch in cooperating with a notch 283 cut in the periphery of 35 plate 200. Early in each eject cycle the side of the notch 280 acts as a cam face to rock the lever 279 in a clockwise direction, moving down an arm 284 connected thereto by pin and slot connection 285. The arm is fastened to one end of shaft 511 40 the other end of which carries a member 287 with an insulation finger 288 for opening and closing contacts 286 and 291.

The initial movement of cam lever 279 serves 45 to open contacts 286, but contacts 291 are closed later in the operation when a projection 289 on cam plate 200 strikes the end 282 of the lever, rocking it further in a clockwise direction and lifting finger 288 against contacts 291. This final lifting movement serves also to restore lever 271 (Fig. 7) which is rocked counterclockwise by link 276 attached to member 287 by stud 280.

As the plate 200 moves in a clockwise direction, at about the mid-point of the operation, another cam face 293 strikes the end of lever 279 and rocks it a slight amount in a clockwise direction. When the lever is so operated, the arm 284 and a link 172 connected thereto at 294 are lowered. It is mentioned hereinbefore that this link is joined to detent 191 by pin and slot connection 195. It is through this connection that the detent 191 is 55 rocked a slight amount in a clockwise direction at the mid point of the eject cycle. This is done to permit a free return motion of the line spacing shaft 178 under control of the connections from the ejecting mechanism.

The machine is provided with devices for guiding the record strip as it enters the carriage. For this purpose a frame 530 (Fig. 11) is secured to the tabulating frame and holds a shaft 531 60 to which a removable sheet holder 533 may be fastened. The upper part of the sheet holder is formed in the shape of a pair of channels 534 and 535 through which the paper may pass in moving down over the guide 74 on frame 66. 65 The holder 533 may hold the record material in a

roll or fan-folded forms with or without carbons.

Certain forms of record material are provided with perforations along the outer edges, which perforations are adapted to be used in feeding one or a plurality of such sheets with interspersed carbons. Figs. 10 and 11 show pin feed mechanism which may be attached to the carriage and removed whenever ordinary paper material is used. The side frames 77 of the carriage support pairs of studs 536 and 537 upon which a pair of pin feed side frames 538 may be assembled. The frames 538 are formed with a pair of grooves fitting around the studs 536, 537 but readily removable therefrom. The frames carry a rotatable shaft 539 upon which is assembled a pair of pin feed wheels 540. Referring to Fig. 10, it is seen that each wheel is formed with a bushing 541 carrying a key 542 located in a key slot 543 cut along the length of shaft 539. 20 By means of this construction the pin feed wheel 540 may be shifted along shaft 539 to accommodate any width of record material. The bushing 541 carries the locating screw 544 which may be turned to fasten the wheel to the shaft to 25 prevent axial movement. The shaft 539 also carries a number of wheels 545 similar to wheels 540 in all respects except the omission of the pin feed projections appearing on the feeding wheels. These last mentioned wheels are used 30 to support the paper at any point between the wheels 540.

At the right end of shaft 539 (Fig. 10) is fixed a gear 546 in mesh with an idler gear 547 (Fig. 11) pivoted on stud 548 on side frame 538. This gear 35 547 meshes with another gear 549 pivoted at 550 on the bottom of the left frame 538. The last mentioned gear forms a removable driving connection with an idler pinion 551 pivoted on shaft 552 located in the carriage side frame 77. This 40 gear 551 meshes with the platen drive gear 90 already mentioned. Through this described train of gearing all motions of the platen shaft 69 in line spacing or ejection is transmitted to shaft 539 for the feeding of perforated sheets. 45

Cooperating with the pin feed wheels 540 is a pair of grooved rollers for holding the record material down into engagement with the projections on the wheels. These devices are mounted on a shaft 553 braced across the top of frames 538. An arm 554 holds each of the guide rollers 555 in position above the related wheel 540. The guide arm 554 is held in position by a screw 556 attaching the arm in any selected position along shaft 553. Arms 554 are formed with a cam projection 557 cooperating with a leaf spring 558 secured to the frames 538. If the arms 554 are rocked in a clockwise direction (Fig. 11) through an angle of about ninety degrees, the spring 558 engages behind projections 557 and holds the rollers 555 out of engagement with wheels 540. 55

The right side frame 538 is formed with an offset flange 559 covering the gear 546. Another guard in the shape of a projection 560 is fastened to the side of frame 77 in position to cover the platen driving pinion 89. 60

Before considering the wiring connections of the automatic carriage control devices, it is believed well to outline the operation of the tabulating machine with which the devices cooperate. The printing devices of such a machine are illustrated in Fig. 1 and the adding, printing group control and other control devices are shown diagrammatically in Fig. 12B. Most of the mat- 70 75

ter of interest in connection with the present case is described in detail in Patent No. 1,762,145.

The general details of construction of the machine are well known in the art and described in said patent, consequently there will be given herein only a brief explanation of such parts thereof as are necessary to an understanding of the present invention. It will be helpful in understanding the invention herein if it be noted that cam contacts identified by the letter L on the circuit diagram are operated by the tabulating mechanism through connections to the motor TM operative during listing operations, while the cam contacts identified by the letter P are operated by the resetting and total taking mechanism through the power of the motor RM.

Referring to Fig. 12B, the record cards are successively fed from a stack and advanced past the upper analyzing brushes UB and exactly 20 one machine cycle later past the lower analyzing brushes LB. Suitable wires connect these brushes to a plugboard terminating in sockets 313 and 314 respectively. The plugboard also includes sockets 315 which are connected to the accumulator magnets AM. As the perforated cards pass 25 the upper brushes, a card lever is engaged by the cards to cause closure of card lever contacts UCL and hold them closed as long as cards continue to feed past the upper brushes.

As the cards pass the lower brushes their 30 index points instantaneously close circuits through the proper lower analyzing brushes LB to energize accumulator magnets AM. As usual, the timed energization of these magnets control 35 mechanism for entering data corresponding to the card reading on the accumulator wheels.

When any magnet AM is energized, it causes 40 contacts 316 to close, energizing a printer magnet PM to select the type corresponding to the entered data for printing. In this fashion the accumulated or entered items may be listed.

In Fig. 1 is shown the printing mechanism through which the type bar 53 is positioned relatively to the platen 51 to bring the proper type 45 317 opposite the platen. The listing shaft 311 driven by the tabulating motor TM is provided with a cam 318 cooperating with a roller 319 carried by an arm 320 operatively connected to a shaft 321. As the cam rotates, shaft 321 is 50 rocked in a clockwise direction and an arm 322 secured thereto and linked at its free end to printing cross-head 323, serves to raise the type bars 53 in synchronism with the movement of the record cards past the analyzing brushes so 55 that the type 317 successively pass printing position opposite platen 51. The type bar 53 is arrested under control of printing magnet PM, which, when energized, attracts its armature 324 and through a call wire 325 releases latch member 326, normally holding stop pawl 327.

When the pawl is so released, it is spring operated to engage the ratchet teeth 328 formed on the type bar 53 to prevent further upward movement of the type bar, thus holding a particular 60 type 317 in printing position. The usual hammers 329 are provided to impel the type against the platen.

During tabulating and listing operations the 65 machine is driven by the motor TM (Fig. 12B) controlled by a group of relays and contacts 70 shown at the top of the sheet. The circuit which serves to maintain the motor TM in operation is as follows: from left side of line 309 through motor TM, relay 330, clutch magnet 331, motor relay 332, its contact points 333 (closed while the

motor is running), wire 334, wire 400, wire 411 (Fig. 12A), contacts 392, 393, 405 and 565, wire 412 (Fig. 12B), upper card lever contacts UCL, wire 390, automatic control relay points 335, wire 494, contacts 401, contacts P3, and the right side 5 of line 310. This circuit maintains the motor TM in operation as long as cards continue to feed through the machine to hold contacts UCL closed and as long as the series of carriage controlled contacts remain closed.

During total taking operations the machine is driven by a reset motor RM controlled by a group of circuits, contacts and relays designated generally at 350. Shaft 312 (Fig. 1) is connected to be rotated by the reset motor during total taking. A cam 336 on the shaft cooperates with an arm 337 on shaft 321 to lift the type bars 53 in synchronism with the rocking of contact levers 338 (Fig. 12B).

These levers cooperate with the stepped cams 20 339 on the accumulator wheels and serve to read the total amount registered thereon by closing contacts 340 in series with the printing magnets PM which then stop the type bars in the proper printing position in the manner noted herein- 25 before.

With the machine adjusted for listing data from each card passing the brushes, the following circuits are completed through the lower brushes: from line 310, contacts P3, L33, wire 400, 30 contacts LLCL1, wire 351, impulse distributor 353, contact plate 341, through the perforation in the card, brush LB, socket 314, connection wire 342, socket 315, magnet AM, contacts 343, and wire 344 to left side of line 309.

Energization of magnet AM will cause opening of contacts 343 to interrupt this circuit and closure of contacts 316 to complete the printing circuit from line 309, wire 344, contacts 316, print magnet PM, wire 345, contacts LP2, switches 40 346, 347, contacts 348 closed during listing operations, to line 310.

The major and minor automatic group control system used in the tabulating machine will be briefly described to bring out certain selective 45 switching features. One form of such a control system is fully disclosed in Bryce Patent No. 1,933,308. The usual automatic control magnets are shown at 431 (Fig. 33) and are provided with the usual series contacts to prevent sparking at 50 the analyzing brushes. Each control magnet is adapted to be plugged in series between related upper and lower analyzing brushes to effect automatic control from any card column.

The automatic control contacts 432 of which 55 one is associated with each control magnet, are arranged to close individually when the corresponding control magnet 431 is energized and all of them are opened simultaneously towards the end of each tabulating or listing cycle. When 60 the control perforations on successive cards under the upper and lower analyzing brushes agree, all control contacts 432 which are properly plugged for automatic control, close at some time during the cycle, while when the control perforations fail to agree, one or more of the contacts fail to close.

The automatic control contacts 432 are all 65 connected in series and a socket 433 is provided 70 between each pair of them so that any number of them may be utilized and the control split into major and minor sections at any point. Under such arrangement when a group change occurs in the minor section total printing takes 75

place under control of the accumulators of the tabulator and certain ones thereof are reset.

When a group change occurs in the major section, the same procedure follows as on a minor change and in addition, totals are printed from other accumulators of the adding devices and the entire apparatus zeroized.

Cam control contacts L3 govern the operation of the machine under major control and cam control contacts C1 govern the operation of the machine under minor control. Both of these contacts are normally closed but open an instant towards the end of each tabulating or listing cycle. The contacts L3 may be plugged in parallel with the control contacts 432 selected for major control and the contact C1 may be plugged in parallel with the control contacts 432 selected for minor control. As shown, contacts C1 are in parallel with minor automatic contacts 432 associated with magnets 431 numbered from 1 to 3 and contacts L3 are in parallel with the other major automatic contacts.

The shunt formed across cam contacts L3 by major control contacts 432 extends from the upper terminal of contacts L3 through wire 434, wire 435, plug wire to socket 433, the terminal of the connected major control contacts 432 in series, thence through the last major control contacts 432 whose other terminal is plugged to upper card lever relay contacts UCL1, closed by cards under the upper brushes as long as major group control is operating, thence to line 310 to which is connected the other side of contacts L3. The switches 436 and 437 should be opened for group control operation. The parallel connection including the major control contacts 432 and cam contacts L3 is in series with a major control relay MA2 while the parallel connection including the minor control contacts 432 and cam contacts C1 is in series with a minor control relay MI2. The major control relay is provided with back contacts 438 and front contacts 439 while the minor control relay is provided with back contacts 440 and front contacts 441. The front contacts of the major and minor control relay contacts connect the relay coils directly to main line 309.

A stick circuit for the major control relay extends from main line 309, through front contacts 439 and major control relays MA2 and MA, and through the parallel connection L3 and wire 442 to line 310, or wires 434, 435 and major control contacts 432 and UCL1 to the main line 310. This circuit will be interrupted to deenergize the major control relay MA2 by the opening of cam contacts L3 at the end of any listing tabulating cycle during which any of the major automatic control contacts 432 fail to close, due to disagreement of major classification perforations in the controlling record cards.

The stick circuit for the minor control relay MI2 extends from main line 309, front contacts 441, minor relay coils MI2 and MI, zero button control magnet ZB, wire 443, contacts C1, contacts L3, and wire 442 to line 310. When the contacts C1 are opened to test the minor control circuit, if there is no change, the magnets remain energized by a circuit from line 309, contacts 441, magnets MI2, MI and ZB, wire 444, minor and major control contacts 432, contacts UCL1 and line 310. It will thus be obvious that a change in the major group data deenergizes both major and minor control relays at the end of the cycle, while a change in minor group data alone, deenergizes the minor control relay only.

Deenergization of these relays, opens the front contacts 439 and 441 and closes the back contacts 438 and 440.

The ultimate result of thus deenergizing the major and minor control relays is to force two reset cycles by the former to permit successively major and minor total printing and to force only one reset cycle by the latter. The back contacts 438 of the major control relay connect the usual motor control relay MCM and the reset control magnet RCM to the main lines 309, 310 for energization, and the back contacts 440 of the minor control relay connect the same magnets in a similar way through a parallel circuit.

Deenergization of either the major or minor control relay energizes the motor control relay MCM and reset control magnet RCM and they remain energized until both the major and the minor control relays are again energized. As explained in the patent to Daly and Page, No. 1,762,145, referred to hereinbefore, energization of motor control relay MCM opens the contacts 335 to stop the tabulating motor TM and prevent it from restarting until the motor control relay MCM is again deenergized.

The energization of reset control magnet RCM opens the contacts 445 to prevent the cam contacts P1 from closing a shunt of one cycle duration around contacts 350, thus sustaining the reset clutch magnet and the reset motor RM and forcing successive reset cycles until the reset control magnet RCM is again deenergized.

During each reset cycle, cam contacts LP6 make and break and directly after they break, cam contacts LP7 make and break. Cam contacts LP6 connect major control relay MA2 to the line 309 through the front contacts 441 of minor control relay MI2. Hence the closure of cam contacts LP6 energizes major relay MA2 only if the minor relay has been previously energized and, since deenergization of the major control relay always entails deenergization of the minor control relay, the closure of these contacts during the first reset cycle is not effective. The closure of cam contacts LP7 during the first reset cycle reenergizes the minor control relay MI2 which in turn re-establishes its stick circuit. If the major control relay is energized at this time with its back contacts 438 open, which will be the case if a group change has occurred in the minor control section alone, this energization of the minor control relay, opens the back contacts 440, breaks the circuit of motor control relay MCM and reset control magnet RCM, and contacts 335 and 445 close causing interruption of reset and resumption of tabulating after a single reset cycle.

If the major control relay has been deenergized by a major group change, at the end of the first reset cycle in which the minor relay is energized, the back contacts 438 remain closed and provide a circuit for the motor control relay MCM and the reset control magnet RCM, thus holding the contacts 335 and 445 open to force a second reset cycle.

During this second cycle the closure of cam contacts LP6 effects energization of major control relay MA2, establishing its stick circuit and opening the back contacts 438 to deenergize motor control relay MCM and reset control magnet RCM. The reset is then interrupted at the end of the second cycle and tabulating may be resumed.

The major and minor control features are not limitations in the machine as they can be made

ineffective if desired, and the machine operated either under straight automatic control or last card operation. The switch 436, if closed, short circuits the cam contacts L3 and throws the entire bank of automatic control contacts 432 in parallel with the cam contacts C1. It also furnishes a current path for the major control relay exclusive of the contacts L3 and any of the automatic control contacts 432. Under these conditions the major control relay MA2 remains energized constantly and the minor control relay MI2 controls the machine for straight automatic control. If the switch 437 is closed as well, a permanent current path is also provided for the minor control relay to maintain it constantly energized and the machine is adapted for last card operation if none of the magnets 431 is connected in series with any column of upper and lower brushes.

It is noted that extra magnets MA and MI are provided in minor and major group control devices. The magnet MA of the major control side of the wiring is adapted to be energized whenever the regular control magnet MA2 is so conditioned by agreement between successive cards of a group. The other magnet MI is connected in series with the minor control magnet MI2 and serves to follow the energization of this magnet.

Associated with these magnets MI, MA are contacts shown in Fig. 12A used to control the line space and eject devices of the present invention.

When the carriage control switch CS is closed the carriage motor CM is energized, providing the contacts in series therewith are closed. Either the speed control contact 157 must be closed denoting a slow speed gear train selection or the feed control contact 499 in parallel therewith must be closed for a feed of $3\frac{1}{2}$ inches or less. Another door control contact DCC is closed by the assembly of the cover casting 139 over the carriage control mechanism. The motor circuit may be traced through line 309, wire 355, motor CM, contacts DCC, either contact 157 or 499, wire 356 and switch CS to line 310.

A number of contacts in the control mechanism are operated according to the presence or absence of record cards in the tabulator. The cards in passing under the lower brushes of the tabulator, operate a lever to close contacts LCL. These contacts are in series with pick-up magnets LCP which are energized over a circuit from line 309, through wire 357, magnets LCP, contacts L31 closed in item entering operations, contacts LCL closed by the card lever, and line 310. Magnets LCP close a contact 358 in line with holding magnets LCH. The circuit through magnets LCH may be traced from line 309 through contacts L21 normally closed, magnets LCH, contact 358 and wire 359 to line 310.

An interlock relay magnet IM is normally energized, but is deenergized to prevent line spacing and tabulator operation as soon as an ejection operation is started. The magnet IM is controlled by contacts 286 which are opened on ejection as noted hereinbefore with reference to Fig. 9. The circuit through magnet IM includes line 309, wire 360, magnet IM, contacts 286, wire 356, switch CS and line 310. The contacts controlled by magnet IM are described hereinafter.

The ejection control magnet EM is energized in many ways to feed the record through a pre-determined distance after each item or total,

at the end of a form, and after a minor or major total.

The closing of switch IES conditions the devices for ejection after a single printing operation. When contact L30 closes on every item entering operation, a circuit through magnet EM may be followed from line 309, magnet EM, contacts 360, wire 361, switch IES, wire 362, contacts L30, switch 363 and wire 364 and 356 to line 310. The closing of contacts P8 on total printing, with switch 363 closed, directs a somewhat similar circuit through magnet EM for tabulating operation.

With switch IES opened, the end of form contacts 269 may be used to control ejection. It is explained hereinbefore how these contacts are closed by the settable lever 274 (Fig. 7). The circuit includes line 309, magnet EM, contacts 360, contacts 366 normally closed, contacts 269, contacts 601, contacts L30, switch 363, wires 364, 20 356 switch CS and line 310. When magnet HSM is connected in the eject circuit by moving switch 363 to the "on" position, contacts 601 open between the closing of contacts P9 and P8 to prevent the energization of magnet HSM when total 25 contacts 373 and end of form contacts 269 are closed in the same cycle. The energization of HSM is wanted when a sheet reaches the end of a form as explained hereinafter.

If it is desired to get an ejection feed after 30 an automatic minor total print, the switch 368 may be lowered to the "on" position. Then the eject magnet is energized over connections involving line 309, magnet EM, contacts 360, contacts 367 closed by the deenergization of magnet MI, wire 369, switch 368, wire 370, contacts P9, wire 356 and line 310.

A major group controlled eject operation is selected by closing switch 371 and opening switches 368, IES and 363. Then the eject circuit follows 40 the path from line 309 through magnet EM, contacts 360, contacts 367, wires 369, 372, switch 371, contacts 373 closed by deenergization of magnet MA, contacts P9, wire 356 and line 310.

The energization of eject magnet EM is accompanied by the energization of an interlock relay magnet TIM wired in parallel therewith through wires 374 and 375. This magnet TIM 45 interrupts the operation of the tabulator until the eject operation is completed. It takes effect quicker than the interlock magnet IM to open associated contacts 392 to prevent an auto start of the tabulator after a total print and before the eject mechanism can get started to open contacts 286. The energization of TIM is sustained by the closing of associated holding contacts 376 connected by wire 377 in series with contacts 286. As soon as interlock magnet IM is deenergized and made ineffective by the opening of contacts 286, magnet TIM is deenergized. 60

If a head spacing operation is selected to follow after an ejection cycle, the switch 368 is lowered to the "on" position to put head space control magnet HSM in series with the eject magnet EM. Then magnet HSM is energized with 65 eject magnet EM when the end of form contacts 269 close. This is done when listing a large number of items that continue from one form to the next form. As the end of the first form is reached, it is desired that the heading space at 70 the top of the next form be skipped to avoid printing items on the preprinted heading. To do this, magnet HSM automatically initiates a number of line spacing operations subsequent to an ejecting operation.

The head space magnet serves to close contacts 378 in series with a skip magnet SM which controls stopping of the printer and successive energization of the line space magnet LSM as explained hereinafter.

On certain forms of records it is desirable to skip a space between the printed heading and the first printed items or amount. The heading may be printed under control of one or more perforated record cards 379 (Fig. 8A) such as name and address cards. The last card of the heading group is punched with a special perforation 380 to control the successive energizations of the line space magnet LSM to feed the record the required space. The special perforation is sensed when the card passes under the lower brushes and a skip relay magnet SM is energized. The circuit through magnet SM may be traced from line 309 (Fig. 12A) through contacts 498 normally closed, wire 381, magnet SM, wire 382, contacts L32 closed as the special index point is sensed, plug wire 383 (Fig. 12B) to the lower brush LB sensing the column in which the special perforation is presented, and through contact bar 341 to impulse timer 353, wire 351, contacts LCL1, wire 400, contacts L33 and P3 to line 310.

The energized magnet SM closes contacts 384 to establish a holding circuit, closes contacts 566 to energize magnet LSM, and opens contacts 565 to deenergize the tabulating motor TM and prevent printing during space skipping.

The holding circuit for magnet SM may be followed from line 309 through contacts 498, wire 381, magnet SM, contacts 384, wire 399, wire 412 (Fig. 12B), contacts UCL, wire 390, contacts 335, wire 494, contacts 401, P3 and line 310. The same sort of an energization of magnet SM is initiated by the head spacing magnet HSM when it closes contacts 378 in series with magnet SM and in parallel with contacts 384. Thus, magnet SM may be made effective in either of two ways, to start line spacing operation directly after an eject operation as controlled by magnet HSM, or to start spacing operation after printing the last line of a heading as controlled by the sensing of a special perforation. A depression of stop key contacts 401 prevents spacing at any point in the operation.

The line spacing operation started by energization of magnet SM and closing of contacts 566 continues until contacts 498 are opened to deenergize magnet SM, open contacts 566 and deenergize magnet LSM. Contacts 498 are operated after a predetermined number of line spaces selected by the positioning of lever 517 (Fig. 7) described hereinbefore.

The line space control magnet LSM (Fig. 12A) is energized in a number of ways. It is operated to space on item entry, total print, major group controlled total printing, head spacing after ejection and card controlled skip spacing after printing of a heading.

During item entering when contacts L34 close, a circuit is established through line 309, magnet LSM, interlock contacts 385 closed except during ejection, contacts 386, contacts L34, contacts 387 closed by a hand lever, switch CS and line 310. On total printing operations contacts P10 close to initiate line spacing through line 309, magnet LSM, contacts 385, 386, wire 388, contacts P10, wire 356, switch CS and line 310. An extra spacing operation is initiated on major group totals by the closing of contacts 373 and P9 and a circuit from line 309 through magnet LSM, contacts 385, 386, wire 388, contacts L44, switch

371 not opened except when ejecting on major changes, contacts 373 closed on a major change, contacts P9, wire 356, switch CS and line 310. Contacts L44 are provided to prevent a back circuit through eject magnet EM and contacts L34 5 on the last listing cycle prior to a major change. Contacts L44 do not close until after the opening of contacts L34.

Other hand set contacts 600 are closed in listing condition. These contacts are arranged in parallel with contacts 373 and switch 371 so that during listing a double line space is fed after every total cycle regardless of whether it is minor or major. But in tabulating with contacts 600 opened, a double space results only on a major 15 group change.

For head spacing or space skipping, contacts 566 close as already explained to complete a circuit through line 309, magnet LSM, contacts 385, 386, wire 388, wire 415, contacts 566, wire 412 20 (Fig. 12B), contacts UCL, wire 390, contacts 335, wire 494, stop key contacts 401, contacts P3 and line 310.

At the bottom of Fig. 12A it is seen that four contacts 392, 393, 405 and 565 are arranged in series. When any one of these contacts is opened, the tabulating motor TM is deenergized and printing is stopped. This is done to allow time for space skipping and ejection between record card feeding and printing operations. It 30 is already explained how magnet SM opens contacts 565 during space skipping operation. And with reference to Fig. 7 it is explained that contacts 405 are opened when the end of form lever 274 strikes latch 273 to initiate an eject cycle. 35 Contacts 393 are closed by interlock magnet IM and opened when this magnet is deenergized by the opening of contacts 286 during an eject cycle.

Contacts 392 are normally closed but are opened by interlock magnet TIM as soon as an 40 eject operation is initiated by the energization of magnet EM.

A switch 395 may be closed to provide a shunt around contacts 392, 393 and 405. This is done to prevent the printer from stopping on high 45 speed ejection operations. The tabulating motor TM sustaining circuit through wires 411, 412 and contacts 392, 393, 405 and 565 is traced hereinbefore.

In the regular tabulating mechanism (Fig. 12B) when auto start switch 391 is closed the machine is conditioned to automatically restart the tabulating motor TM when P2 closes after a resetting operation. Other auto start contacts 291 and 292 are provided by the present invention to start the printing tabulator motor TM after ejection, head spacing or skip spacing operation.

It is described hereinbefore how contacts 291 (Fig. 9) are closed near the end of an ejection 60 operation. It is also explained how contacts 292 (Fig. 7) are closed at the end of a space skipping operation. Now referring to Figs. 12A and 12B a circuit may be traced through either of these contacts and the tabulating motor. From line 65 309 (Fig. 12B) current flows through motor TM, magnet 330, clutch magnet 331, relay coil 332, auto start switch 391, wire 413 (Fig. 12A) thence through either contact 291 or 292, wire 414, contacts 565 closed except when skip spacing, wire 70 412 (Fig. 12B), contacts UCL, wire 390, contacts 335, wire 494, contacts 401, P3 and line 310.

A switch 398 is placed in series with contact 291 so that the auto start connections may be broken and restarting of the tabulator is not 75

brought about automatically by the completion of an eject cycle.

Since the basic novel features of the invention are shown and described it will be understood that various omissions, substitutions and changes in the form and details of the devices illustrated, and changes in operation may be made by those skilled in the art without departing from the spirit of the invention. It is the intention, therefore, to be limited only as indicated by the scope of the following claims.

What is claimed is:

1. In a machine of the class described, means for printing a heading on a record form, means for controlling said printing means to print items on the same form with the heading, means for automatically feeding the form a predetermined number of line spaces after printing the heading and before printing the first item, means for initiating operation of said feeding means, and separate means cooperating with said feeding means for determining the number of line spaces to be fed between the heading and the first item.
2. In a machine of the class described, means for printing a predetermined number of lines of heading print on a record sheet divided into forms, devices settable for a predetermined number of lines of spacing, means automatically initiated by the printing of the last line of heading print on a form and controlled by said devices for automatically feeding the sheet a predetermined number of line spaces, and means for controlling said printing means to print items on the same form after automatic feeding.
3. In a record controlled machine, means for sensing the records, means under control of said sensing means for printing on a record sheet, means for stopping said printing means after a predetermined number of printing operations, devices settable for a predetermined number of lines of spacing, means under control of said sensing means and said devices for feeding the record sheet a predetermined number of line spaces, and means under control of said feeding means for restarting said printing means.
4. In a machine controlled by record cards divided into groups with the last card of a group carrying a special perforation, means for sensing the data on the cards, means under control of said sensing means for printing data appearing on the records on a record sheet, means for feeding the record sheet in line spacing, means for controlling the sheet feeding means to space the sheet a predetermined number of line spaces between the printing groups, and means under control of said special perforation for initiating operation of said controlling means.
5. In a machine controlled by perforated record cards divided into groups, one group containing heading data and another group containing item data, the last card with heading data also containing a special perforation, means for sensing the perforations on the cards, means under control of said sensing means for printing the data sensed on a record sheet, a driving means, means for line spacing the record sheet, a clutch between said driving means and the spacing means, a magnet for controlling the closing of said clutch, means under control of said special perforation for energizing said magnet, a cam adapted to be set for a certain number of cycles of the machine, means under control of said spacing means for operating said

cam as spacing takes place, and means under control of said cam for deenergizing said magnet after a required length of blank space on said record sheet is fed between the last line of the printed heading data and the line which is to receive the first item print.

6. In a machine of the class described, means for entering data into the machine, means under control of said entering means for printing the data on a record sheet, means for line spacing said sheet between printing operations, means for shifting said sheet a plurality of line spaces, a driving means, a high speed train of gearing, a low speed train of gearing, and means for connecting either train of gearing between said driving means and said shifting means to control the movement of the sheet.

7. In a machine of the class described, means for entering data into the machine, means under control of said entering means for printing the data on a record sheet, means for line spacing said sheet between printing operations, means for shifting said sheet a plurality of line spaces, a driving means, a high speed train of gearing, a low speed train of gearing, means for connecting either train of gearing between said driving means and said shifting means to control movement of the sheet, and means cooperating with both trains to prevent the connection of one when the other is free for connection.

8. In a machine of the class described, means for entering data into the machine, means under control of said entering means for printing the data on a record sheet, means for line spacing said sheet between printing operations, means for shifting said sheet a plurality of line spaces, means for setting said shifting means to move the sheet a predetermined number of line spaces, a driving means, a high speed train of gearing, a low speed train of gearing, means for connecting either train of gearing between said driving means and said shifting means to control the movement of the sheet, and means for preventing operation of said shifting means when said setting means is adjusted for shifting the sheet more than a certain number of line spaces at the same time that the high speed gear train is connected.

9. In a record controlled machine, means for sensing data on the records, means under control of said sensing means for printing the data on a record sheet divided into forms, means for ejecting a form after printing thereon, a high speed train of gearing, a low speed train of gearing, and means for connecting the high speed gearing to said ejecting means for ejecting short forms and connecting the low speed gearing to said ejecting means for ejecting long forms.

10. In a sheet feeding device, a driving means, a toothed driving member connected to said driving means, a toothed driven member engaging said driving member, means for moving said driving member relative to said driving means for taking up slack between the driving and driven members, and means under control of said driven member for feeding the sheet.

11. In a sheet feeding device, a driving part, a toothed driving member movably connected to said driving part, a toothed driven member adapted to be engaged by said driving member, a latch for holding said driving member retracted on said driving part, means for tripping said latch to free said driving member for movement relative to said driving part to take up

- slack between the driving and driven members, and means under control of said driven member for feeding the sheet.
12. In a machine of the class described, means for printing data on a record sheet, means for line spacing said sheet, an ejecting frame provided with a series of teeth, connections to said line spacing means comprising a toothed member cooperating with said teeth and moved along said teeth as the sheet is fed in line spacing, means for initiating a sheet ejecting operation, means operated early in the ejecting operation for moving said toothed member into contact with one of said teeth, and means under control of said initiating means for operating said frame to engage said member at any of said teeth to move said connections and operate the spacing means to eject the record sheet.
13. In a sheet feeding device, an ejection frame, a toothed slide movable on said frame, a pair of cranks pivoted on said frame and carrying said slide, a cam cooperating with said slide to move it relative to said frame and said cranks, a toothed block, means for moving said block across said slide while line spacing, means for initiating a sheet ejection operation, means under control of the last mentioned means for moving the cam to bring one of the teeth on said slide against a tooth on said block, connections from said block to the sheet for feeding the sheet, means under control of said initiating means for moving the ejection frame, the slide, the block and said connections, and means for operating said cranks to move the slide out of cooperation with said block to permit the restoration of the block after ejection.
14. In a machine of the class described, means for printing data on a record sheet, means for line spacing said sheet, means for ejecting said sheet, means for initiating operation of said line spacing means, means for initiating operation of said ejecting means, and a common manipulative means which may be operated in either of two ways to operate either initiating means.
15. In a machine of the class described, means for printing data on a record sheet, means for line spacing said sheet, means for ejecting said sheet, an armature adapted to be tripped for initiating operation of said line spacing means, a magnet automatically energized to trip said armature, a second armature adapted to be tripped for initiating operation of said ejecting means, a second magnet automatically energized to trip said second armature, and a manipulative lever with connections to both armatures and arranged so that when the lever is rocked in one direction the first armature is tripped and when the lever is rocked in the other direction the second armature is tripped.
16. In a machine of the class described, means for printing data on a record sheet, a driving means, means for ejecting said sheet, a clutch for connecting said ejecting means with the driving means, means for automatically operating said clutch for ejection, and means operated by said ejecting means early in the ejecting operation for locking said clutch in an operated position.
17. In a machine of the class described, means for feeding paper in line spacing, means for ejecting the paper a plurality of line spaces, means for regulating said line spacing means to feed the paper a predetermined number of spaces after an ejecting operation, and means under control of said ejecting means for initiating operation of said line spacing means.
18. In a machine of the class described, means for printing on a record sheet, means for feeding said sheet in line spacing, means for electing said sheet a plurality of line spaces, means for regulating said line spacing means to feed the sheet a predetermined number of spaces after an ejecting operation, means under control of said ejecting means for initiating operation of said line spacing means, and means under control of said operating means for preventing operation of said printing means while feeding the sheet through the predetermined space.
19. In a machine of the class described, means for entering data into the machine, means under control of said entering means for printing the data on a record sheet, means for line spacing said sheet, and means under control of said entering means for initiating a predetermined number of operations of said line spacing means, and means under control of said initiating means for preventing operation of said printing means while said line spacing means is operating the predetermined number of times.
20. In a machine of the class described, means for entering ordinary and special data into the machine, means under control of said entering means for printing the data on a record sheet, means for line spacing said sheet, means for controlling said line spacing means to space the sheet a plurality of lines, adjustable means for setting said controlling means to cause a variable and predetermined number of operations of said line spacing means, and devices under control of said special data entering means and operable as an incident to the entry of special data for initiating operation of said controlling means.
21. In a machine of the class described, means for entering ordinary and special data into the machine, means under control of said entering means for printing the data on a record sheet, means for ejecting said sheet a plurality of line spaces, means for operating said line spacing means a predetermined number of times, means under control of said ejecting means for initiating operation of said operating means, and other means under control of said entering means when entering special data for initiating operation of said operating means.
22. In a machine controlled by record cards, means for sensing data on the cards, means under control of the sensing means for printing the data on a record sheet, means for feeding the record sheet in line spacing, means under control of said sensing means for initiating a predetermined number of operations of said line spacing means, and means under control of said initiating means for stopping operation of said sensing means as the sheet is fed said predetermined number of spaces.
23. In a machine controlled by record cards, means for sensing data on the cards, means under control of the sensing means for printing the data on a record sheet, means for feeding the record sheet in line spacing, means for ejecting said sheet a plurality of line spaces, means for regulating said line spacing means to feed the sheet a predetermined number of spaces after an ejecting operation, means under control of said ejecting means for initiating operation of said line spacing means, and means under control of said operating means for stopping operation of said sensing means while the sheet is fed said predetermined number of spaces.
24. In a machine of the class described, means

- for printing on a record sheet, means for feeding said sheet in line spacing, means for ejecting said sheet a plurality of line spaces, means for regulating said line spacing means to feed the sheet a predetermined number of spaces after an ejecting operation, means under control of said ejecting means for initiating operation of said line spacing means, means under control of said operating means for preventing operation of said printing means while feeding the sheet through the predetermined space, and means under control of the line spacing means for restarting operation of said printing means.
25. In a machine for printing and feeding a record sheet divided into forms, means for printing on said sheet, means for line spacing said sheet, means for ejecting said sheet from form to form, means for controlling said line spacing means for skipping a predetermined space between a heading and the first item of a form, means for controlling said line spacing means for head spacing the sheet in continuing items from one form to the next, means for stopping and restarting said printing means during ejection, and other means for stopping and restarting said printing means during space skipping and head spacing.
26. In a machine for printing heading data and interspersed amount data on a record sheet divided into forms, means for entering the data into the machine item by item, means under control of said entering means for printing the items of heading and amount data on the sheet, means for line spacing said sheet, means for detecting the approach of the end of the first form, devices for ejecting a form and skipping the space on the next form reserved for heading print, means under control of said detecting means for initiating operation of said ejecting and skipping devices when the end of the first form is reached, and means for operating said devices to eject the second form and insert the third form to the beginning of the third heading space when all the related amount data is printed above the end of the second form.
27. In a machine controlled by record cards divided into sets according to the nature of the data thereon, with the last card of certain sets having a special perforation, means for sensing the data on the cards, means under control of said sensing means for printing data appearing on the cards on a record sheet, means for line spacing and feeding the sheet to separate the printed data relating to different sets of cards, means for controlling said feeding means to space the sheet a predetermined distance between the printed data of said sets, and means under control of said special perforation for initiating operation of said controlling means, and other devices under control of said records for initiating operation of said controlling means.
28. In a machine controlled by record cards divided into groups with each group including heading cards and amount cards, the last heading card containing a special perforation, means for sensing the data on the cards, means under control of said sensing means for controlling the printing of the data of the records on a record sheet, sheet feeding devices, means for controlling said devices to space the sheet from the position where it receives the last line of heading print to a position to receive the first line of amount print, and means under control of said special perforation for initiating operation of said controlling means.
29. In a machine for printing data on a sheet divided into forms under control of record cards divided into groups with each group including address cards and amount cards, the last address card containing a special perforation, means for sensing the data on the cards, means under control of said sensing means for controlling the printing of the data of the records on said sheets, sheet feeding devices, group control devices for sensing changes in the card groups, means under control of said group control devices for operating said feeding devices to eject the printed form and feed the next form into position to receive the first line of address printing, means under control of said special perforation for controlling said feeding devices to feed the form in position to receive the first line of amount print after the printing of the last address line, means for detecting the approach of the end of a form during amount printing, and means under control of said detecting means for controlling said feeding devices to eject the form filled with item impressions and feed the next form directly to the position for receiving the first line of amount print.
30. In a machine for printing heading data and interspersed sets of amount figures on a record sheet divided into forms, certain of said sets of figures requiring more than one form, means for entering the data into the machine item by item, means under control of said entering means for printing the items of heading and amount data on the sheet, sheet feeding devices, means for controlling sheet feeding when the last of a set of amount figures is printed above the end of a form, means under control of said controlling means for operating said feeding devices to eject the printed form and feed the next form into position to receive the heading data, means operative as an incident to the completion of the heading printing for controlling said feeding devices to feed said next form to put a space between the heading and the first line on which the first amount is printed, and means operative on the approach of the end of a form during amount printing for controlling said feeding devices to eject the form filled with amount figures and feed the next form to skip the heading space and stop in position to continue amount printing on the first line of said next form.
31. In a machine for printing address data and amount data on a record sheet divided into forms, each form having an upper address printing area and a lower amount printing area, means for entering the address and amount data, means under control of said entering means for printing said data on said sheet, spacing means for feeding the sheet with relation to said printing means from the address area to the top of the amount area on the same form, shifting means for moving the sheet with respect to said printing means from any point in said amount printing area of one form to the top of the address area on the next form, said spacing means and shifting means being operative together to move the sheet relative to said printing means from the bottom of the amount printing area of one form to the top of the amount printing area on the next form, and devices for automatically initiating operation of said spacing and shifting means.
32. In a machine controlled by successively presented records, power operated line spacing mechanism, a magnet for initiating operation of the power operated line spacing mechanism, elec-

trical analyzing means operative to analyze data designations in said records, and means controlled by predetermined designations in said records through the analyzing means for governing the operation of said magnet.

33. In a machine controlled by successively presented records, automatic line spacing mechanism including a magnet for controlling the operation of said mechanism, electrical means for analyzing data designations in said records; a relay connected to said analyzing means and operative, when a predetermined designation is sensed by the analyzing means, to permit energization of the magnet; and means for energizing the magnet subject to control by said relay.

34. In a machine controlled by successively presented records, means to automatically space a record sheet including a magnet and means tending to energize said magnet at least once for each record, contacts in circuit with said magnet, 5 an electrical device for analyzing data designations in said record, and electrical means connected to said analyzing device for operating said contacts in response to predetermined designations in said records.
